CLAIM

The ornamental design for legs for an easel, as shown and described

DESCRIPTION

FIG. 1 is a right rear perspective view of an easel showing my new design, the left rear perspective view being the mirror image;

FIG. 2 is a rear elevation view of the easel; and,

FIG. 3 is a right side elevation view of the easel, the left side elevation view being the mirror image.

The broken lines showing the framed display board, the front projecting tray, and the cross braces between the short legs are for illustrative purposes only and form no part of the claimed design.
